DIVIDED MULTIPLEX CHANNEL SYSTEM

David S. Hulfish, Chicago, Ill., assignor to Teletype Corporation, Chicago, Ill., a corporation of Delaware

Application September 23, 1939, Serial No. 296,181

11 Claims. (Cl. 178—52)

This invention relates to telegraph signaling systems and more particularly to systems for transmitting a plurality of messages concurrently from an invariable number of transmitters over a single transmission path to a corresponding invariable number of receivers respectively related to the transmitters.

An object of this invention is the transmission of concurrently stored messages one by one or part by part to several telegraph receivers in rotation.

Another object is the utilization of high percentage of line time by the expedient of associating with the transmission path for major time periods only those transmitters in which messages or parts of messages are stored and are awaiting transmission, and for minor time periods those transmitters in which little or no such material is instantly stored.

A still further object of this invention is to provide apparatus whereby a transmission path when assigned to a plurality of transmitters and associated receivers will be utilized to a high percentage of time by transmission in substantially continuous manner from a single transmitter to a single associated receiver whenever all other transmitters assigned to the path are idle, or the path will be shared substantially equally between any two active transmitters when all other transmitters assigned to the path are idle, or will be shared substantially equally by all transmitters operating in rotation when all transmitters assigned to the path are in active condition.

A further object is to effect the described divided transmission over one channel of a synchronous multiplex system, the divisional transmission circuits constituting subchannels within the multiplex channel.

A further object is to attain automatically a phase relation between and among the receivers and transmitters of the subchannels after the main distributors of the multiplex system have been started and synchronized, and before transmission over the subchannels is begun.

A further object is to provide means for restoring subchannels into true phase relation automatically while operating, in case such phasing has been disturbed.

Another object is so to dispose the locations of the divers and sundry parts of apparatus within the structure of the invention that a degree of supervision over the instant conditions of transmission may be exercised at a substation by users

of the transmission facilities provided by the invention.

A further object is to phase a substation start-stop transmitter by a phasing signal generated at a central office, utilizing novel circuits.

A further object is to operate a start-stop transmitter and a remotely located associated start-stop receiver completely in synchronism, rather than according to present practice of operating the two start-stop distributors at nonsynchronous rotational speeds but electrically in phase for the code signaling character impulses.

To achieve the objects of this invention, means is provided for transmitting over a common path from a plurality of subchannel transmitters line by line or message by message. As a provision for successive operation and for preventing any station from monopolizing the common path, means is provided for limiting the length of time during which any station may occupy the path continuously without offering opportunity to other transmitters to seize the path should one of the other transmitters be in active condition for transmission.

25 A feature of tape storage is provided, and to enable users of the service to supervise the condition of transmission it is provided in a modified form of the invention that the storage and supervision may be effected at the originating substation.

20 Synchronism in operation of the transmitting and receiving start-stop mechanism is attained by provision of a new method and novel apparatus for operating a start-stop system, including 30 circuits for starting the transmitter and the receiver simultaneously by a single starting signal impulse which passes through the two starting magnets in series or through equivalent relays, as an improvement over prior practice of starting

35 a transmitting distributor and then delaying transmission of a character code signal until the transmitter first has generated a starting signal impulse to start a remote receiver. The present invention decreases the baud index figure of the 40 currents in the extension arm as compared with prior structures having a like character-per-minute speed.

45 A more complete understanding of the invention may be had from the following description 50 taken in conjunction with the accompanying drawings wherein,

Fig. 1 illustrates a circuit system for a multiplex office, showing details for transmitting messages into a multiplex channel;

Fig. 2 illustrates a circuit system for a multi-

plex office showing details for receiving messages from a multiplex channel;

Fig. 3 shows circuit details of apparatus for generating signals at the central office shown in Fig. 1;

Fig. 4 shows details of retransmission mechanism and of one substation recorder;

Fig. 5 shows circuit details of central office and substation equipment suitable for co-operation with the system shown in Fig. 1 and providing for message storage at the substation; and

Fig. 6 shows details of retransmission mechanism and substation recorder alternative to the similar system shown in Fig. 4.

By combining Figs. 3, 1, 2 and 4, left to right in the order of mention, there is produced a complete circuit of an embodiment of the invention and by combining in similar manner Figs. 5, 1, 2 and 6, there is produced a complete circuit of a modified form of the invention.

Like numerals refer to like parts throughout the several views. Numerals 1 to 6, inclusive, are descriptive as also are letters shown in the drawings, and these are not to be taken as reference numerals. Assemblies and groups of parts are indicated by leading lines having arrow tips.

In general, a transmission path is equipped at the transmitting end with a distributor of any type which connects the transmission path at all times to one of a plurality of transmitters assigned to that path. Transmitters are connected in rotation and in invariable order to the path. At the remote or receiving end of the path a distributor of any type responds to received predetermined control signal code impulses and connects to the path the corresponding recorders in invariable rotational order. A message is recorded at the transmitting end in a perforated tape and is transmitted from the tape. Interruption of transmission may be effected by a code signal in the tape, by control of a taut tape switch or by a time limit device. Limiting the tenure of the common path by any station or transmitter is accomplished by a timing device or equivalent operated by the transmitting means.

More specifically there is illustrated in Figs. 1, 2, 3 and 4 jointly a typical structure embodying the invention in which a multiplex channel is subchanneled to three tape transmitters and to three start-stop recorders.

Referring to Figs. 1 and 3, a multiplex transmitting distributor 10 has five segments 11 pertaining to one multiplex channel, the segments 11 being connected through five conductors in cable 18 to transmitting contacts 12 in five transmitting relays 13 individually numbered 1 to 5. Windings of relays 13 are connected through five conductors in branching multiple to contacts 14 of three tape transmitters 15, 16, and 17.

A subchannel distributor, indicated generally as 20, comprises a continuously driven power shaft 21 and a frictionally driven cam sleeve 22 with ratchet 23 and four cams 24, 25, 26, and 27. Ratchet 23 is controlled by magnet 28 through armature dog 29 to stop the cam sleeve 22 in any one of four stop positions, as determined by the teeth of the ratchet 23. In each of its stop positions the cam sleeve 22 will position one of its cams to operate its follower to close one of the four sets of cam controlled contacts 31, 32, 33, and 34. Sixth-impulse relay 35 is energized over a circuit controlled by segments in distributor 10 and, in turn, controls by its front contact a circuit which extends either through code-con-

nected contacts 36 or contacts 37 of relays 13 and then through windings of magnets 38 and 28 to grounded battery.

A motor 40 drives a snail 41 to propel a snail follower 42 which is pivoted upon the armature of magnet 38 and which will engage and close the contacts 43. Collector ring 44 of distributor 10 is connected in circuit with the winding of transmitting relay 45, the armature and contacts of which connect either positive or negative grounded battery to the apex of duplexing relay 46 and thence through line 47 to a remote receiving duplexing relay 48, Fig. 2.

There are shown in Fig. 3 three identical tape storage assemblies, one of which comprises a tape perforator 50 which may be either keyboard controlled or remotely controlled to perforate a tape 51, a relay 52, a relay 53, and a tape senser device including magnet 54, armature 55, feeler slides 56, feeler slide contacts 14, and taut tape switch 57.

A circuit extending from ground and back contact of relay 35, Fig. 1, and thence through resistor 115 to branching multiple conductors may be completed through any one of the three cam-controlled contacts 31, 32, and 33, and from a closed one of said contacts through the winding of one of the relays 53, 120, 124 to grounded battery, the described circuit extending also in a branch conductor through a winding of relay 52 and through a front contact of relay 52 to grounded battery when relay 52 is in operated condition, a condition which is attained initially only by current in a circuit from battery through a winding of relay 52 and through contacts of a taut tape switch 57 to ground. A circuit from battery through the winding of magnet 54 may be completed to ground either through back contact and armature of relay 53 when unenergized, or through armature and front contact of relay 52 when energized.

Referring to Fig. 2, the multiplex receiving distributor 60 has five segments 61 pertaining to the channel identified with segments 11 (Fig. 1) connected through five conductors in a cable 62 to windings of five receiving relays 63 individually numbered 1 to 5.

Holding circuits for relays 63 extend from ground through winding and contacts of each relay, winding of sixth-impulse-cutout relay 64 and back contact of relay 65 to grounded battery, or alternatively through front contact of relay 65 to grounded battery or through armature 66 and front contact of relay 67 to grounded battery. Contacts 68 of relays 63 prepare energizing circuits for relays 70, Fig. 4, and the prepared relays 70 may be subsequently energized by current from grounded battery through a winding of each prepared relay 70, contact of relay 95, contact 68, and armature 71 and contact of relay 67 when momentarily closed in response to current in a circuit including battery, the winding of relay 67 and segments 72.

Relays 70, when energized, form each a holding circuit from grounded battery through its winding and contacts 73 and cam controlled contacts 111 to ground.

A subchannel receiving distributor, indicated generally as 80, is similar to the distributor 20, Fig. 1, and comprises a continuously driven power shaft 81 and a frictionally driven cam sleeve 82 with ratchet 83 and four cams 84, 85, 86, and 87. Ratchet 83 is controlled by magnet 88 through armature dog 89 to stop the cam sleeve 82 in any one of four stop positions, as

determined by the ratchet teeth. In each of its stop positions, the cam sleeve 82 will position one of its cams to operate its follower to close one of the three sets of cam controlled contacts 91, 92, or 93, or to change the contactual relations of the contact set 94.

Each of the cam controlled contact sets 91, 92 and 93 is connected in a circuit with grounded battery and the winding of a line switching relay 95, 96, or 97, respectively. Relay contacts 98 and 99, connected in code manner, correspond to similar contacts 36 and 37 in Fig. 1.

Retransmission contacts 100 in storage relay set 70 are connected to the character signal segments of retransmitting distributors, Fig. 4, of which the distributor 105 is shown in detail. A further conductor 102 extends from contacts of relays 64 and 67 and thence in branching multiple through contacts in line switching relays 95, 96, and 97 to the starting magnets of the said retransmitting distributors, as shown by magnet 196. The collector ring 107 of the distributor 105 is connected to an extension arm line conductor 108 which extends to a substation telegraph receiver which may be of any desired type and which is illustrated as the type of recording receiver fully illustrated and shown in United States Patent No. 1,904,164 issued to S. Morton et al. The magnet 109, Fig. 4, corresponds to the magnet 9 in the Morton et al. patent and shall be taken to represent an entire receiving equipment according to the Morton patent.

Operation of the system illustrated in Figs. 1, 2, 3, and 4 is as follows:

In Figs. 1 and 3, presume that no perforator 50 has been operated and accordingly all of the tape switches 57 are in operated condition with closed contacts, relays 52 are in energized condition, and magnets 54 are in energized condition, all feeler slides are in withdrawn position, all relays 13 are unenergized, and all contacts 12 are set open or to spacing position. Resultantly, code contacts of the set 36 are all closed. In Figs. 2 and 4, the relays 63 and 70 are unenergized and all relay contacts 68 are in open or spacing position.

Initial phasing of the subchannel distributors 20 and 89 will be effected by code signals sent automatically from distributor 20, presuming that multiplex distributors 10 and 60 have been started and have been phased. In distributor position No. 1, as shown (Figs. 1 and 3), with armature dog 29 in engagement with the No. 1 tooth of ratchet 23 and with contacts 31 closed, the contacts of tape switch 57 of transmitter 15 open and magnet 54 of transmitter 15 energized, brushes of distributor 10 will transmit a "blank" code signal of five spacing intervals producing or continuing the closed condition of relay contacts 36 and 99. The ensuing sixth-impulse currents from segments 39 and 12 will energize momentarily the relays 35 and 67 which, in the case of relay 35, will generate an impulse in a circuit including ground, front contacts of relay 35, contacts 36, windings of magnets 38 and 28, and grounded battery. In the case of relay 67, an impulse will be generated in a circuit including ground, contact 71 and armature of relay 67, contacts 99, left-hand contacts of set 94, winding of magnet 88, and grounded battery. Armature dogs 29 and 89 are operated simultaneously, cam sleeve 22 rotates all cams 24, 25, 26, 27 into stop position No. 2, while cam sleeve 82 will move from one random position to its next position,

except that if sleeve 82 had been in its No. 4 position with the contact set 94 in operated position, the last described circuit will not be closed, and sleeve 82 will remain in No. 4 position.

At the next revolution of the brushes of distributor 10 with contacts 32 closed and taut tape in transmitter 16, a "blank" code signal of five spacing impulses will be transmitted, energizing the magnets as before and advancing the cam sleeve 22. The cam sleeve 82 also will be advanced unless by its progress from a random position it has reached its No. 4 position in which case it will remain in its No. 4 position.

In like manner a rotation of the brushes of distributor 10 will cause the cam sleeve 22 to pass from its No. 3 position and into its No. 4 position, and at that time cam sleeve 82 will be in its No. 4 position either reaching No. 4 position simultaneously with sleeve 22, or having waited for sleeve 22 to reach its No. 4 position.

In its No. 4 position, cam sleeve 22 closes contacts 34 to energize and operate relay 2 of set 13, setting up "line feed" code signal in contacts 12 of relays 13. In response to transmission of "line feed" signal by brushes of distributor 10, the No. 2 relay of set 63 is energized. Sixth impulses flow in relays 35 and 67. A repeated sixth-impulse then flows in a circuit, Fig. 1, including ground, front contact of relay 35, contacts 37, winding of magnet 38, winding of magnet 28, and grounded battery, and a further repeated sixth-impulse flows in a circuit, Fig. 2, including ground, contact and armature 71 of relay 67, contacts 98, right-hand contacts of set 94 in operated condition, winding of magnet 88 and grounded battery. Magnets 28 and 88 are energized simultaneously and cam sleeves 22 and 82 are stepped at the same time into position No. 1, thus having been brought into phased relation automatically. An extension arm equipment, represented by perforator 50, which may be manually operated or remotely controlled, now has been operatively connected by functions of contacts 31, Fig. 1, to a multiplex channel and thence to an extension arm represented by conductor 108, Fig. 4, and recorder 109 by functions of the cam contacts 91, Fig. 2, and relay 95, energized over an obvious circuit.

Presume that while contacts 32, 33, and 34 were operating, perforator 50 had begun operation to provide tape for transmission and that the contacts of taut tape switch 57 accordingly were opened before the present closing of contacts 31. At cessation of the sixth-impulse through segments 36 and at release of the armature of relay 35, contacts 31 form a circuit including grounded battery, winding of relay 53, contacts 31, resistor 115, back contacts of relay 35, and ground. Current in this circuit energizes and operates the relay 53 which breaks the energizing circuit of magnet 54 and releases the armature 55 to release the sensing slides 56 which, in turn, operate the transmitter contacts 14 to energize relays 13 in code manner. Presuming character A to have been sensed in the tape 51, relays 1 and 2 of set 13 now will be energized, which is the condition illustrated in Fig. 1.

Brushes of distributor 10 now traverse segments 11 to operate relays 45, and 48, and resultantly relays 1, 2, of relay set 63 which close their holding circuits through winding of relay 64 and contacts of relay 65 to grounded battery, thus preparing operating circuits for relays 1 and 2 of set 70. This is the condition illustrated in Fig. 2. A sixth-impulse of current in relay 35 gener-

ated by segments 39 now operates armature and contacts which close no circuit, because both contact set 36 and contact set 37 are open, but which open the described circuit of relay 53 permitting de-energization of relay 53 and consequent energization of magnet 54 over an obvious circuit. Upon energization of magnet 54, and operation of armature 55, the sensing slides 56 are withdrawn from the tape and the tape is stepped. At the end of the sixth-impulse, the armature of relay 35 recloses the energizing circuit of relay 53, which, in turn, opens the energized circuit of magnet 54, armature 55 is released, and the sensing slides rise to set upon the code relays 13 the signal code for the next character to be transmitted. Distributor 20 remains unmoved and perforator 50 remains connected to distributor 10.

A sixth-impulse of current in relay 67 generated by segments 72 simultaneously with the impulse energizes relay 67 to close contact and armature 71 to complete the energizing circuit of relays 1 and 2 of set 70. The energizing circuit includes ground, contact and armature 71 of relay 67, conductor 110, contacts 68, conductors in cable 101, contacts in operated relay 95, lower windings of relays 70 and grounded battery, each operated relay 70 forming its own holding circuit from grounded battery through upper winding of relay 70 and cam contact 111 in distributor 105 to ground. Operated relay 67 also operates armature 66 to shunt the closed contacts of relay 65 and operates another armature to energize relay 65 over an obvious circuit, the armature 66 acting to close its contacts before the relay 65 opens its back contact, thus preserving the continuity of the holding circuits of the relays 63. The armature 112 of relay 67 also closes a circuit including ground, front contact 172 and armature 112 of relay 67, armature and front contact of relay 64, conductor 102, sixth-impulse contact of relay 95 now held energized by cam contacts 91, starting magnet 106 and grounded battery. Magnet 106 is energized, its latching armature is attracted, and distributor 105 starts.

At the end of the sixth-impulse in relay 67, armature 71 retires from its contact to open the energizing circuit of relays 70. Armature 112 in relay 67 also opens the described sixth-impulse circuit over conductor 102 to de-energize the magnet 106. Armature 66 retires from its contact to remove the shunt from contacts of relay 65 and a further armature 113 opens the contacts of the energizing circuit of relay 65 which releases its slow-to-release armature to produce a transit-time break in the holding circuit of relays 63, thus de-energizing all relays 63 and also de-energizing the relay 64.

Although armature 71 in the relay 67 had connected the ground potential to conductor 110 and to the contacts of relays No. 1 of sets 98 and 99, no circuit was completed through those contacts, magnet 88 was not energized and sub-channel distributor 80 remains in its set position, relay 95 remains energized and distributor 105 with extension arm conductor 108 remains connected to the multiplex channel.

Distributor 105 now transmits to line conductor 108 and to recorder 109 a starting impulse followed by five character code impulses under control of contacts 100 of which contacts 1 and 2 now are closed, and finally a stop impulse is transmitted from grounded battery through resistor 114. During the rotation of distributor 105, an ensuing character code has been transferred to relays 13, Fig. 1, in overlap manner. Distribu-

tor 105 is slightly faster in rotation than distributor 60 so that the brush arm invariably comes to rest in engagement with the armature dog of magnet 106. Character transmission from transmitter 15 to recorder 109 continues as described until at the end of a line, and in response to "carriage return" code signal, the transmitter 15 operates the relay 4 alone in the set 13. This results in transmission of "carriage return" code signal to distributor 60 and in energization of relay 4 alone in set 63. Resultantly, the coded contacts 36 and 99 are closed when the brushes of distributors 10 and 60 engage their respective segments 39 and 72 to generate sixth impulses.

In Fig. 1, relay 35 is energized by the sixth impulse and is operated to close a circuit including contacts 36 and magnets 38 and 28. Armature of magnet 38 lifts follower 42 from snail 41 to be returned by its spring. Armature of magnet 28 frees the cam sleeve 22 to rotate, and the cam sleeve rotates for a distance of one tooth, opening the cam controlled contacts 31 and closing the cam controlled contacts 32. At the end of the sixth impulse, a circuit from ground through armature and back contact of relay 35 and through resistor 115 will be completed through contacts 32 and magnet 120 instead of through contacts 31 and magnet 53 as before the stepping of the cam sleeve 22. Thus, transmitter 15 has been released and transmitter 16 has been qualified for operation.

In Fig. 2, relay 67 is energized by the sixth impulse, and its four armature members are operated. Armature 71 connects ground over conductor 110 and contact of operated relay 4 of set 68, a conductor in cable 101 and a contact of relay 95 to energize and operate relay 4 in set 70 which forms its holding circuit through its contact 72 and through cam controlled contacts 111 to ground, thus setting on relay set 70 the code signal transmitted from relay set 13. Armature 66 closes its contacts to shunt the contacts of relay 65. Armature 113 closes its contacts to energize relay 65. Armature 112 closes its contacts to connect ground through armature and contact of relay 64 and through the sixth impulse contact of relay 95 to the starting magnet 106, thus starting the distributor 105. Armature 71 also has effected ground connection over conductor 110 through closed code contacts 99 and through left-hand contacts of set 94 to magnet 88 which attracts its armature 89 and frees the cam sleeve 82, which rotates until stopped by engagement of tooth No. 2 with the armature stop dog 89. Operation of the cam sleeve 82 will open the contacts 91 and close the contacts 92, thus de-energizing the line switching relay 95 and energizing the line switching relay 96. Despite the opening of contacts of relay 95, the distributor 105 continues transmission of the code signal stored in the relay set 70 and just before the distributor 105 stops, the cam control contacts 111 are operated momentarily to break the holding circuits of any energized relays in set 70, in this instance relay 4.

By energization of relay 120 and resultant de-energization of transmitter magnet 121, a code signal sensed in tape 118 of the transmitter 16 is registered upon relays of set 13. The ensuing rotation of synchronous distributors 10 and 60 will register this code signal on relays of set 63. Then through closed contacts of energized relay 96, the code signal is transferred to the relays of a set corresponding to set 70 associated with the distributor 119 and with the extension arm

line conductor 122 of a recorder, not shown. Ensuing code signals from transmitter 16 will be transmitted through contacts of relays 96 and through distributor 119 until a code signal for carriage return results in closing the coded contact sets 36 and 99 producing a stepping rotation of cam sleeves 22 and 82 to disconnect transmitter 16 from communication with retransmitter 119 and to connect transmitter 17 into communication with retransmitter 121.

Upon transmission of a carriage return code signal generated in transmitter 17, the cam sleeves 22 and 82 step into their position No. 4, thus closing contacts 34 which sets the code signal for line feed on relays 13, as described in the discussion above concerning phasing. The cam sleeves 22 and 82 step into their position No. 1 completing a cycle of transmission with slack tapes.

Should any tape be taut, a "blank" code signal will be transmitted, as described in the description of phasing above. Thus, the transmitter having no tape supply will be connected to the multiplex channel for a time period of one code signal only. But a transmitter having an available tape supply for transmission will retain connection with the multiplex channel until transmission of a carriage return signal, or until a tape supply has become exhausted.

Should a tape supply become exhausted, the exhausted tape will become a controlling condition at the beginning of a sixth impulse. When the last available code signal perforation in the tape 51, Fig. 3, has been set upon relays 13, Fig. 1, and has been transmitted over the multiplex channel, the ensuing sixth impulse will energize and operate relay 35 which will interrupt current in relay 53 and permit closure of the energizing circuit of magnet 54. Attraction of armature 55 withdraws slides 56 from the tape 51 and steps the tape, thereby operating the taut tape switch 57 and closing its contact and energizing over an obvious circuit the relay 52 which, by attraction of its armature, closes a shunt upon the closed contacts of relay 53 to control energization of magnet 54. Relay 52 also prepares its holding circuit to be closed by relay 35.

At the end of sixth impulse, the relay 35 recloses its back contact, re-energizing the relay 53 and completing the holding circuit of relay 52. Relays of set 13 now are in spacing condition because relay 52 continues the energization of magnet 54 and all slides 56 are held down. Transmission of "blank" code signal, thus registered on relays 13, results in stepping the cam sleeves 22 and 82 in the manner described in the description of phasing above.

The object of the holding circuit of relay 52 is to prevent mutilation of the transmission of the "blank" signal registered upon relays 13 as a result of operation of the perforator 50 at random in a transmission cycle.

Should the perforator 50 be controlled by a remote transmitter of a tape printer system, there will be no carriage return code signals in the tape 51. Accordingly, the snail 41, follower 42, and contact 43 are provided for advancing the cam sleeves and the magnet 38 is provided for resetting the parts mentioned. After a predetermined lapse of time during which neither contacts 36 nor contacts 37 have been closed, the follower 42 will have been driven by snail 41 into position to close contacts 43, thus connecting resistor 123 in shunt with the winding of relay 53

and rendering that relay marginal. Presume that closure of contacts 43 occurs at an instant when relay 35 is energized and relay 53 is operated, then current will be reduced in relay 53 but will remain sufficient to hold the armature of relay 53 so that no immediate result is effected. Upon energization of relay 35, the relay 53 is de-energized, and upon de-energization of relay 35 the current in the winding of relay 53 will be insufficient to operate the armature of the relay because of the shunting effect of resistor 123. Hence, the contacts of relay 53 continue to hold the magnet 54 energized, the slides 56 are held down, and "blank" code signal is registered upon the relays of set 13. Transmission of this code signal followed by a sixth impulse steps the cam sleeves 22 and 82, as described for initial phasing, and the follower 42 is raised for restoration by its spring as a result of momentary energization of magnet 38.

20 The carriage return code signal, which effects rotation of the cam sleeves 22 and 82, is also retransmitted by a distributor, such as 105, because the code signal is stored in the relay set 70 at the time that the relay 95 is de-energized and the distributor has been started by the impulse over conductor 102. In the case of "blank" code signal, however, the code signal is not retransmitted because of the sixth impulse suppression relay 64 which estops the starting impulse in conductor 102. In the case of the line feed code signal for advancing the cam sleeves 22 and 82 out of position No. 4, the code signal is not retransmitted because with the cam sleeves in position No. 4, all 35 of the relays 95, 96, 97 are de-energized and no extension arm line is connected.

25 Rephasing of the subchannel distributors 20 and 80 automatically during transmission in case the initial phasing has been disturbed may be provided for by arranging the receiving recorders as 109 to effect line feed as well as carriage return functions in response to receipt of a carriage return code signal, the line feed signal being only by cam contacts 34 for phasing or irregularly for tabulation purposes in regular transmission.

30 A modified form of transmitting equipment which may be substituted for the transmitter 15, Fig. 3, is illustrated in Fig. 5. A tape sensing transmitter 131 at a substation at 132 has its transmitting contact tongues 133 connected to the code impulse segments of a transmitting distributor 134, the collector ring 135 of which is connected over line conductor 136 to the feed ring 137 of a central office receiving distributor 138. Character code segments 1 to 5 of distributor 138 are connected to windings of code signal relays 1 to 5 of set 140. A starting circuit includes grounded battery 141, resistor 142, armature 143 and front contact of relay 144, armature 145 and back contact of slow operating relay 146, winding of starting magnet 147 of distributor 138, resting segment R, brush 148, and feed ring 137 of distributor 138, line conductor 136, collector ring 135, brush 149, segment R, and starting magnet 150 of substation distributor 134, conductor 151, and contacts 152 of taut tape follower 153 to ground. De-energization of tape sensing magnet 154 permits slides 155 to rise for the purpose of sensing the tape 156, and re-energization of magnet 154 withdraws the slides 155 and steps the tape 156.

35 A feature of the modified form illustrated in Fig. 5 is to locate the storage tape 156 at the perforator 157 and keyboard 158 rather than 75 at the central office, thereby keeping the sub-

station operator informed as to the amount of tape remaining at any time untransmitted.

In operation of the structure illustrated by Fig. 1 and Fig. 5 combined, with ample tape 156 at the substation and with contacts 152 closed as shown, relay 144, shown in operated condition, will be de-energized by contacts of relay 35 at the beginning of each sixth impulse, the armature 160 then being retracted to open the obvious holding circuits of all relays of set 140, while armature 161 also is retracted to form a path for discharge of condenser 162, the path thereafter remaining as a shunt around the winding of relay 146. Opening the holding circuit of relays 140 releases all such relays and removes all ground connections from relays 13. At the end of each sixth impulse, the armature of relay 35 will be retracted to close a circuit through contacts of relay 35, resistor 115, contacts 31, winding and contacts of relay 144 and grounded battery 163. Operation of relay 144 closes the starting circuit described above, pending operation of the armature of the slow operating relay 146. Current in this circuit energizes the two starting magnets 147 and 150, attracting their armatures and releasing brushes 148 and 149 for rotation. Upon opening of contacts of armature 161, current will flow through winding of slow-to-operate relay 146, attracting armature 145 and interrupting the described starting circuit. Brushes 148 and 149 now rotate synchronously in phase and in unison. Brush 164 breaks the obvious energizing circuit of magnet 154 which now releases its armature permitting the rising of slides 155 to sense a code combinational record in tape 156. Contacts 133 thus are adjusted to register a sensed code combination, and the registered code signal is transmitted from battery 165 through contacts 133, distributor 134, line conductor 136 and distributor 138 to relays 23 of set 140 which form their holding circuits to armature 160 and which, by their right-hand armatures, set the registered code signal upon the relays of set 13 for transmission by distributor 10.

In the event of taut tape in the substation 132, opening the contacts 152, the relays of set 140 will be released by armature 160 as described to delete the used code signal. The described starting circuit then will be found open at contacts 152, the distributors 134 and 138 will not start and there will be no new registration on the relays of set 140, thus leaving relays of set 140 and resultantly the relays of set 13 in condition of blank code signal or all spacing. Accordingly, the distributors 20 and 80 are advanced as described for operation of the structure of Fig. 1 in co-operation with the structure of Fig. 3.

Signaling impulses generated by the structure illustrated in Fig. 5, when transmitted through the structures of Fig. 1 and of Fig. 2 are effective for control of the structures illustrated in Fig. 4 as described.

To obtain a lower baud value in a recorder line as 108, a system according to Fig. 6 may be utilized. Fig. 6 is to be combined with Fig. 2, substituting distributor 170 for the distributor 105 to form a complete circuit diagram of a receiving system.

In Fig. 6, distributor 170 differs from the distributor 105, Fig. 4, by having fewer segments, and by having starting magnet 171 included in series with the substation selector magnet 179 which corresponds to magnet 109, Fig. 4. The 75

starting circuit for magnets 171 and 179 extends from ground through contact of relay 180, conductor 173, magnet 171, segment R, ring 175, line conductor 178, and magnet 179 to grounded battery. The controlling circuit extends from ground through contact 172 and armature 112 of relay 61, Fig. 2, contacts of relay 64, conductor 102, sixth contacts of relay 95, conductor 181, Fig. 6, and winding of relay 180 to grounded battery.

In operation of the system of Figs. 2 and 6 jointly, receipt of a code signal is registered on relay set 63 after which a momentary energization of sixth-impulse relay 67 transfers the code signal through contacts 68, Fig. 2, and contacts of relay 95 to relays 176, Fig. 6, and also supplies a starting impulse over the controlling circuit and starting circuit, traced in detail above, de-energizing the magnets 171, 179, and starting the central office distributor 170 and the substation distributor, not shown. These two distributors then make one rotation in phase and in synchronism, transferring the registered code signal through contacts 177 to the substation selector magnet 179 in response to which code signal a record is made at the substation. Holding circuits for relays 176 are as described for relays 70.

The invention has been illustrated in connection with specific illustrative systems which are capable of modification without departing from the spirit or scope of the invention, the invention being described only by the scope of the appended claims.

What is claimed is:

1. In a synchronous multiplex system, a multiplex channel, a plurality of transmitters, a like plurality of receivers, means to connect to said multiplex channel said plurality of transmitters one by one in invariable rotational order and said plurality of respectively associated receivers in similar invariable rotational order, means to store in each said transmitter independently of others of said transmitters a variable quantity of code signal indicia, and means to maintain any transmitter in connection with said channel for a period of time which is variable under control of the quantity of said stored signal indicia.

2. In a synchronous multiplex system, a telegraph line, a pair of distributors connected to said line and located at remote points, a pair of sequence switches connected to said distributors respectively, means for driving said sequence switches singly or simultaneously into a phasing position in response to a predetermined code signal, and means for driving said sequence switches simultaneously out of said phasing position in response to another predetermined code signal.

3. In a synchronous multiplex system, a telegraph line, a pair of distributors connected to said line and located at remote points, a pair of sequence switches connected to said distributors respectively, means for driving said sequence switches singly or simultaneously into a phasing position in response to a predetermined code signal, means for driving said sequence switches simultaneously out of said phasing position in response to another predetermined code signal, means in one of said sequence switches when in phasing position for generating said second mentioned code signal, and means for applying the generated second mentioned code signal whereby both of said sequence switches rotate simultaneously.

4. In a telegraph system, a substation, a cen-

tral station, an extension circuit connecting said stations, a synchronous multiplex distributor at said central station connected to said extension circuit, a start-stop telegraph distributor connected to said circuit, a start-stop printer at said substation, a start magnet for said start-stop distributor, a start magnet for said printer, and means controlled by said multiplex distributor for energizing said start magnets simultaneously.

5. In a telegraph system, a synchronous multiplex line, a multiplex distributor in said line, an extension circuit, a start-stop transmitter and a start-stop receiver connected to said extension circuit, a start magnet for said transmitter, a start magnet for said receiver, and means to energize simultaneously the starting magnets of said transmitter and said receiver, respectively, said means controlled by a contact of said multiplex distributor.

6. In a telegraph system, a synchronous multiplex line, a multiplex distributor in said line, an extension circuit, a start-stop transmitter and a start-stop receiver connected to said extension circuit, a contact in said multiplex distributor, and a single start circuit for said extension circuit including the start magnet of said transmitter and the start magnet of said receiver under the control of said contact of said distributor.

7. In a synchronous multiplex, start-stop extension circuit system, a central station, a substation, a tape sencer and a signal distributor at the substation, a receiving start-stop distributor at the central station, a multiplex distributor at the central station electrically connected to the receiving start-stop distributor thereat, a line circuit connecting the distributor at the substation with the receiving distributor at the central station, and means controlled over said line by a contact in the multiplex distributor jointly with a contact in the tape sencer to control operation of said tape sencer and to regulate the operation of the tape sencer according to the operation of the multiplex distributor.

8. In a synchronous multiplex, start-stop extension circuit system, a central station, a substation, a tape sencer and a signal distributor at the substation, a taut tape switch associated with said tape sencer, a receiving start-stop distribu-

tor at the central station, a multiplex distributor at the central station electrically connected to the receiving start-stop distributor thereat, a line circuit connecting the distributor at the substation with the receiving distributor at the central station, and means controlled by a contact in the multiplex distributor and by a contact of said taut tape switch to control operation of said tape sencer and to regulate the operation of said tape sencer according to the operation of the multiplex distributor when the tape is in a predetermined position.

10. In a telegraph system, a telegraph line, a pair of distributors connected to said line and located at remote points, a sequence switch connected to each of said distributors, means for driving the sequence switches, and means controlled by a predetermined code signal for controlling the operation of said sequence switches to bring them in phase relationship preparatory to telegraphic transmission of intelligence.

15. In a telegraph system, a telegraph line, a pair of distributors connected to said line and located at remote points, a sequence switch connected to each of said distributors, means for driving the sequence switches, means controlled by a predetermined code signal for controlling the operation of said sequence switches to bring them in phase relationship preparatory to telegraphic transmission of intelligence, and means for thereafter operating said sequence switches at variable times during the transmission of intelligence.

20. In a telegraph system, a telegraph line, a pair of distributors connected to said line and located at remote points, a sequence switch connected to each of said distributors, means for driving the sequence switches, means controlled by a predetermined code signal for controlling the operation of said sequence switches to bring them in phase relationship preparatory to telegraphic transmission of intelligence, and means for thereafter operating said sequence switches at variable times during the transmission of intelligence.

25. In a synchronous multiplex system, a telegraph line, a pair of distributors connected to said line and located at remote points, a pair of sequence switches connected to said distributors, respectively, a plurality of transmitters and a plurality of receivers associated with switching connections in said sequence switches, respectively, means for changing said switching connections in said sequence switches at variable intervals and in variable order, and means controlled by a predetermined code signal for controlling the operation of said sequence switches to bring them into phase relationship preparatory to telegraphic transmission of intelligence.

30. DAVID S. HULFISH.
